DESIGN FOR A SHOE

Ernest A. Rainey, Manchester, N. H., assignor to Diamond Shoe Corporation, Brockton, Mass., a corporation of Massachusetts

Application September 20, 1935, Serial No. 58,627

Term of patent 3½ years

To all whom it may concern:

Be it known that I, Ernest A. Rainey, a citizen of the United States, residing in Manchester, county of Hillsboro, State of New Hampshire, have invented a new, original, and ornamental Design for a Shoe, of which the following is a specification, reference being had to the accompanying drawing, forming part thereof.

In the drawing:

The dominating features of the present invention reside in a shoe having its vamp ornamented by means of substantially square areas of perforations, in which areas the center row of perforations is the largest with the rows on either side thereof progressively diminishing in size to the opposite margins of the areas, and each area being placed substantially perpendicular to the adjacent areas.

What is claimed is:

The ornamental design for a shoe, as shown and described.

ERNEST A. RAINY.
